UNITED STATES PATENT OFFICE.

EDWIN A. OLLEY AND FLOYD C. SMITH, OF SYRACUSE, NEW YORK, ASSIGNEES TO CROUSE-HINDS COMPANY, OF SYRACUSE, NEW YORK, A CORPORATION OF NEW YORK.

ELECTRIC SWITCH.

Application filed March 28, 1921, Serial No. 456,248.

To all whom it may concern:

Be it known that we, EDWIN A. OLLEY and FLOYD C. SMITH, citizens of the United States, and residents of Syracuse, in the county of Onondaga and State of New York, have invented a certain new and useful Electric Switch, of which the following is a specification.

This invention has for its object an electric switch which is particularly simple in construction, and highly efficient and durable in use, and especially in which the parts are compactly arranged. The invention consists in the novel features and in the combinations and constructions hereinafter set forth and claimed.

In describing this invention, reference is had to the accompanying drawings in which like characters designate corresponding parts in all the views.

Figure 1 is a plan view of a switch embodying my invention.

Figure 2 is a side elevation thereof.

Figures 3 and 4 are respectively, elevations looking to the right respectively in Fig. 2.

Figure 5 is a sectional view on line 5—5, Fig. 4.

This switch comprises generally, a base, a support mounted on the base, a switch arm mounted on the support and pivoted thereto, an operating lever also pivoted to the support and having an arm extending crosswise of the axis of the switch arm and movable in an arc from either side thereof to the other, and a spring connection between the arm of the lever and the switch arm arranged to throw the switch when the lever has been operated to tension the spring and shift it to the opposite side of the axis of the spring arm to that on which it is located when the movement of the operating lever begins.

The invention further consists in means between the lever and the switch arm to positively shift the same in case the spring fails to act.

1 designates the base which may be of any suitable form, size and construction, here shown as a block of insulating material.

2 is a support here illustrated as including two uprights arranged parallel to each other, this support being preferably U-shaped in general outline and having its

branches forming the uprights and its intermediate portion secured to the base as by screws 3 extending through the base from the rear side thereof through the intermediate part of the support.

4 is the switch arm which is U-shaped in general outline and has its branches 5 extending on opposite sides of the uprights 2 and mounted on the pivots or studs 6 supported by the uprights.

7 is the operating lever here shown as angular in form and pivoted at 8 to the uprights at one side of and parallel to the axis 6 of the switch arm 4, the lever 7 having an arm 9 extending horizontally crosswise of the axis of the pivot 6 of the switch arm 70 and normally arranged on one side of such axis as below the same as shown in Fig. 5 and movable to the other side or above the axis when the switch arm is moved into the position shown in Fig. 2. During the movement of the switch arm across the axis 6, a spring is tensioned and in turn throws the switch arm.

10 designates the spring which is a compression spring coiled about a guide rod 11 suitably pivoted at 12 to the end of the arm 9 of the lever 7 and slidable in an opening 13 formed in the intermediate part of the switch arm, the spring abutting against the inner face of the intermediate part of the switch arm and a shoulder 14 on the inner end of the guide rod 11 near the end of the lever arm 9.

The switch arm or the branches thereof are also formed with spaced apart shoulders 90 or inturned lugs 15, 16 on the opposite side of the axis 6 to that on which the intermediate part of the switch arm is located; and the arm 9 of the lever 7 is formed with laterally extending shoulders 17 movable between 95 the shoulders or lugs 15, 16 in order to engage one of the same when the lever 7 is moved in one direction or the other and throw the switch arm or give a starting impulse thereto in case the spring 10 fails to 100 act. The lugs or shoulders 15, 16, 17 form a positive connection between the operating lever and the switch arm.

18 and 19 are pairs of switch contacts carried by each of the arms 5 of the switch arm, the contacts 18 of each pair coating with terminals 20 for connection to the service wires the terminals rising from the base,

and the contacts 19 of each pair coating with other terminals 21 also rising from the base and spaced apart from the terminals 20.

The contacts 18, 19 are suitably mounted on sleeves 22 of insulation, Fig. 4, mounted on studs 23 carried by the branches 5 of the switch arm and located between blocks or washers 24, 25 of insulation mounted on the sleeve on opposite sides of the contacts. The contacts are thus insulated from the branches 5 of the switch arm.

Barrier plates 26 of insulation are also carried by the branches 5 of the switch arm and interposed between the contacts and being of sufficient radius to lap the inner sides of the terminals and prevent arcing across the contacts 18-18, or 19-19 or the terminals 20-20, or 21-21 through the metal portions of the switch construction.

20 This switch construction is adapted to be mounted in a conduit box having an operating handle movable through the box and engaging the lever 7.

In operation, during movement of the lever 7 to the right from the position shown in Fig. 5, the arm 9 moves about the axis 6 and in so doing compresses the spring 10 until the end or the pivot 12 of the rod 11 passes above the pivot 6 whereupon the switch arm is thrown by the spring into the position shown in Fig. 2. Upon movement of the lever to the left from the position shown in Fig. 2 the reverse of this operation takes place.

35 Owing to the relative arrangement of the axes of the switch arm and the lever handle a particularly compact switch construction is provided.

What we claim is:

40 1. In a switch, a base, a support rising from the base, a switch arm pivoted to the support, and an operating lever pivoted to the support on an axis at one side of and parallel to the axis of the switch arm, the operating lever having an arm extending crosswise of the axis of the switch arm and movable across such axis, a compression spring interposed between the arm of the lever and the switch arm to throw the

switch, the switch arm being also formed 50 with spaced apart shoulders and the arm of the lever being also formed with a shoulder extending between the former shoulders to engage the same and throw the switch arm when the operating lever has been 55 moved far enough to tension and position the spring to throw the switch arm and the spring fails to act, substantially as and for the purpose set forth.

2. In a switch, the combination of a base, 60 a support mounted on the base, a switch, an operating lever pivoted to the support, and connections between the operating lever and the switch arm, switch contacts carried by the switch arm, a barrier carried by and 65 movable with the switch arm and arranged on the inner side of the contacts to prevent arcing across the contacts and terminals on the base with which the contacts coat, the barrierslapping the sides of the terminals, 70 substantially as and for the purpose specified.

3. In a switch, the combination of a base, a support mounted on the base including opposing uprights, a switch arm U-shaped in 75 general form and having the branches thereof extending on the outer sides of the uprights and pivoted thereto, an operating lever pivoted to the support between the uprights and having an arm thereof extending 80 crosswise of the axis of the switch arm and connections between the operating lever and the intermediate portion of the switch arm, pairs of switch contacts carried by and movable with the switch arm, pairs of terminals 85 on the base with which the contacts coat and barriers carried by the branches of the switch arm and arranged between the contacts and said branches, the barrierslapping the inner sides of the terminals, substantially 90 as and for the purpose described.

In testimony whereof, we have hereunto signed our names at Syracuse, in the county of Onondaga, and State of New York, this 29th day of September, 1920.

EDWIN A. OLLEY.
FLOYD C. SMITH.
